DESIGN FOR A GAME DEVICE

Carlo Rubino, Flushing, N. Y.

Application February 25, 1937, Serial No. 67,841

Term of patent 3½ years

To all whom it may concern:

Be it known that I, Carlo Rubino, a citizen of the United States and resident of Flushing, Long Island, in the county of Queens and State of New York, have invented a new, original, and ornamental Design for a Game Device, of which the following is a specification, reference being had to the accompanying drawing, forming a part thereof.

Fig. 1 is a top plan view of a game device, showing my new design.

Fig. 2 is an edge elevational view of the same.

I claim:

The ornamental design for a game device, as shown.

CARLO RUBINO.
